DESIGN FOR A VALANCE CLIP

Richard H. Wright, Cleveland Heights, Ohio

Application December 24, 1938, Serial No. 81,974

Term of patent 7 years

To all whom it may concern:

Be it known that I, Richard H. Wright, a citizen of the United States, resident of Cleveland Heights, in the county of Cuyahoga and State of Ohio, have invented a new, original, and ornamental Design for a Valance Clip, of which the following is a specification, reference being had to the accompanying drawing, forming a part thereof, in which:

Figure 1 is a view in perspective of the valance clip showing my new design; Figure 2 is a side

elevation thereof, and Figure 3 is a rear elevation thereof.

My design comprises a valance clip of the configuration shown, having an elongated depression or groove extending along each side and in parallel relation to points adjacent the extremities of the clip.

I claim:

The ornamental design for a valance clip, substantially as shown and described.

RICHARD H. WRIGHT.
